UNITED STATES PATENT OFFICE.

HENRY TSCHERNING, OF FREEPORT, ILLINOIS, ASSIGNOR TO ARCADE MANUFACTURING CO., OF FREEPORT, ILLINOIS, A CORPORATION OF ILLINOIS.

MOLDING MACHINE.

Application filed November 14, 1925. Serial No. 69,041.

My invention relates to molding machines of the type comprising an invertible table for the flask, and locking means for holding the table in different positions to which it is rotated about its axis; and more particularly to machines comprising means which operate to squeeze the sand in the flask and means whereby the pattern and flask may be separated.

10 My primary object is to provide locking means for the table of such a construction, so constructed that regardless of looseness in the pivotal support for the table, the table will be held against rocking on its support 15 during the operation, or operations, of the machine in which it should be so held to avoid the producing of imperfect molds, as for example in the squeezing and drawing operations. In the squeezing operation it

20 is desired that the table be locked against rocking because if it does rock in such operation the sand will become non-uniformly packed in the flask thus producing a tendency to the tearing of the mold when the pattern is drawn, and in the drawing operation such locking is desired to prevent the pattern from tilting with the table relative to the mold and which would tear the mold or produce distortion thereof.

25 Inasmuch as I have devised my invention for use more particularly in a machine providing for the squeezing of the mold and the drawing of the pattern, I have chosen to illustrate it in such a machine, my improvements being shown as incorporated in a machine of the general construction shown and described in my U. S. Letters Patent No. 1,427,839 granted August 29, 1922.

30 Referring to the accompanying drawings:

Figure 1 is a view in side elevation of the machine disclosed in said patent showing my present improvements incorporated therein. Figure 2 is an enlarged view in side elevation of a portion of the mechanism shown in Fig. 1 and with which my present improvements more directly co-operate. Figure 3 is a broken section taken at the line 3 on Fig. 2 and viewed in the direction of the arrow. Figure 4 is an end view of the invertible pattern-and-flask-carrying table forming a part of the machine illustrated; and Figure 5, a view in front elevation of the machine.

55 The machine shown comprises a base 5

mounted on wheels 6 and from which rise upright guide rods 7 at each end, with slides 8 moving on each end pair of rods, respectively. A pattern table 9 to which the pattern would be attached at the portion 10 thereof, is mounted in the slides 8 to rotate about its longitudinal axis to permit this table to be inverted from the position shown in the drawings throughout 180° and back to the position shown, as desired, the table being equipped with jarring mechanism as described in said patent, the jarring cylinder of which is represented at 11, the table 9 in the jarring operation being inverted from the position shown in the drawings and bearing at its cylinder 11 upon an anvil 12 supported on an upright 13 carried by the base 5 and adapted to be swung laterally into and out of the position shown in Fig. 1.

50 The slides 8, together with the table 9, are adapted to be raised and lowered on the rods 7, by means of links 14 pivotally connected at their upper ends with the slides 8, as indicated at 14^a, and at their lower ends, as represented at 15, to the lower ends of crank arms 16 fixed on the ends of a shaft 17 journaled on the base 5 and adapted to be oscillated, in any suitable manner, as for example by power mechanism (not shown).

55 In the operation of the machine shown which, except as regards the locking feature hereinafter referred to, is the same as that shown in my patent above referred to, the cope, or drag, as the case may be where only one part of the flask is to be produced by the operation of the machine, or both the cope and the drag where both are to be produced by one operation, in which latter case 95 the cope and drag would extend side by side, are applied to the pattern-carrying portion 10 of the table 9, the table, in this operation, being inverted from the position shown in the drawings, the sand for forming the mold 100 is then applied to position, the jarring mechanism set into operation to jar the same, and a board, or boards, as the case may be, then applied to the flask section, or sections, these boards being of a size to extend within the confines of the sides of the flask sections, and with these boards held against displacement, by the clamping devices 20 and 21, the table 9 is rotated on its trunnions, represented at 18, to the position 105 110

shown in the drawings, the slides 8, together with the table 9, having been preliminarily elevated on the rods 7. The slides 8 and table 9 are then lowered upon these rods to cause the boards referred to to bear against the central portion 19 of the member 12 which operates to squeeze the sand into firmly compacted condition in the flask and about the pattern. The operator then releases the lamps 20 and 21, and raises the slides 8 and the table 9 on the guide rods 7 thereby upwardly drawing the pattern out of the mold which remains deposited on the member 12, following which operation the latter is swung laterally on the member 13 to render the mold freely accessible to the operator for removing it from the machine.

It is necessary that means be provided for locking the table 9 in its various positions of adjustment about the axis of the trunnions 18 above referred to, and it is also desirable, and necessary for the production of perfect molds, that the table 9 be held against tilting during the squeezing and drawing operations referred to and this I accomplish by my improved locking means of which the following is a description:

Slidably mounted in one of the slides 8, to be movable toward and away from the adjacent end of the table 9, is a locking bolt 22 which is positioned in direct vertical alignment with the axis of the trunnion 18, this bolt being normally spring-pressed toward the table 9 by a coil spring 23 carried by the slide 8 referred to. The end of the table 9 adjacent this locking bolt contains diametrically-opposed, radially-elongated, openings 24 which are aligned in a plane at a right angle to the face portion 10 of the table, these openings being so disposed that one of them receives the outer tapered end portion 25 of the bolt 22 when the table is in one position about its axis and the other thereof receives this bolt when the table is rotated through 180°, the bolt being withdrawable, against the tension of the spring 23, from the one of the openings 24 which it happens to extend into, for permitting of the rotation of the table 9, by means of a lever 26 fulcrumed at 27 on a stud 28 supported on the one of the slides 8 which carries the locking bolt 22, the lever 26 being pivotally connected between its ends, as represented at 29, to the outer end of the locking bolt.

It will thus be understood from the foregoing description that by providing the radially-elongated openings 24 arranged as stated and positioning the locking bolt 22 in vertical alignment with the axis of the trunnions 18, such looseness as may occur between the trunnions 18 and their bearings will be taken up vertically, without produc-

ing tilting of the table 9, in both the squeezing and "pattern-drawing" operations. 65 Therefore the sand will be uniformly squeezed in the mold and the pattern will be drawn accurately from the mold.

While I have illustrated and described a particular embodiment of my invention I 70 do not wish to be understood as intending to limit it thereto as the same may be variously modified and altered without departing from the spirit of my invention.

What I claim as new, and desire to secure by Letters Patent, is:

1. In a molding machine, the combination of a support, a pattern-carrier pivoted on said support, and locking means for said carrier extending in vertical alignment with 80 the axis of said pivot.

2. In a molding machine, the combination of a support, a pattern-carrier pivoted on said support, and locking means for said carrier extending in vertical alignment with 85 the axis of said pivot, said support and carrier being relatively movable in a vertical plane in the operative position of said locking means.

3. In a molding machine, the combination of a support, a pattern carrier pivoted on said support, and locking means for said carrier comprising interlocking portions one of which is on said carrier, said interlocking portions when in interlocked position extending in vertical alignment with 95 the axis of said pivot and being constructed and arranged to permit relative movement of said portions in a vertical plane.

4. In a molding machine, the combination of a support, a pattern-carrier pivoted on said support, and locking means for said carrier comprising a radially-elongated opening in said carrier and a locking pin on said support in vertical alignment with 105 said pivot and adapted to extend into interlocking engagement with said opening.

5. In a molding machine, the combination of a support, a pattern-carrier pivoted on said support, and locking means for said carrier comprising diametrically-opposed 110 radially-elongated openings in said carrier and a locking pin on said support in vertical alignment with said pivot and adapted to extend into interlocking engagement with 115 either of said openings.

6. In a molding machine, the combination of a support, slide means movable up and down on said support, a pattern-carrier pivoted on said slide means and locking means for said carrier comprising portions on said slide means and said carrier in vertical alignment with said pivot in the locking position.
